CARL J. KANNEWISHER, OF ROCHESTER, NEW YORK

DEVICE FOR TESTING TYPEWRITER RIBBONS

Application filed February 4, 1928. Serial No. 251,806.

The present invention relates to typewriting machines and more particularly to attachments therefor and it has for its object to provide an ordinary typewriter or similar machine with means whereby an inking ribbon can be temporarily attached in such a way as to give an opportunity for testing its quality and durability. The general purpose is to subject a relatively small trial area of the ribbon in a short space of time to a great number of type impacts or impressions or until the repetitions have demonstrated the wear with which, by calculation, the ribbon would become worthless in actual use. The improvements are directed in part toward the provision of a detachable ribbon holding means for this purpose which will be simple and inexpensive in construction and convenient and efficient in use. To these and other ends the invention resides in certain improvements and combinations of parts, all as will be hereinafter more fully described, the novel features being pointed out in the claims at the end of the specification.

In the drawings:

Figure 1 is a front view partly broken away of the platen, type bar guide and associated parts of a typewriter showing an attachment constructed in accordance with and illustrating one embodiment of my invention;

Figure 2 is an enlarged section on the line 2-2 of Figure 1;

Figure 3 is a top plan view of the attachment in one form;

Figure 4 is a perspective view thereof;

Figure 5 is an enlarged section on the line 5-5 of Figure 3;

Figure 6 is a perspective view of a modified form of attachment; and

Figure 7 is a fragmentary elevation of a portion of Figure 1 showing the modified attachment of Figure 6 in position.

Similar reference numerals throughout the several views indicate the same parts.

A familiar standard type of typewriter construction in connection with which I have, in the present instance, illustrated and will describe my invention embodies a cy-

lindrical platen 1 turned by knobs 2 at its ends to feed a sheet or strip of paper (not shown) there around, the paper passing beneath or in rear of a fixed type guide shown generally at 3. Types 4 on pivoted type bars 5 strike through the type guides against the platen and the paper, and an inking ribbon being fed continuously between the type and platen, an inked impression is made upon the paper. The printing point is indicated at A in Figure 1 which is the position of the type in that figure. The inking ribbon being a moving ribbon, as aforesaid, no two successive blows or impacts of the type occur at the same point on the ribbon surface until the whole ribbon has passed through the machine but as the ribbon is reversed and fed back and forth in a well known manner, every point thereof is ultimately subjected to a repetition of its inking function and the number of such repetitions that it will stand determines its life and depends upon various characteristics of quality.

To quickly test such a ribbon for durability, my invention contemplates stretching a short selected length thereof or, for instance, an end of a complete ribbon, across the printing point in a fixed position relatively to the platen so that, without feeding it, successive blows of a type are repeatedly received upon very few, say five or six, points of the surface and, as the paper is fed laterally past the printing point and the platen carriage shifted within restricted limits, a record of the ultimate performance of which the ribbon is capable, is obtained. The record test sheet will show a number of short lines, the first of which will be clear and distinct while the ribbon is fresh and will gradually fade, progressively, until a point is reached where the inked impression is too faint to be satisfactory or useful. This marks the point at which the ribbon, in use, would have to be discarded and the number of lines on the test sheet to this point is an index of the quality and life of the ribbon as, through calculation, this may be used to determine how long an entire working length of such a ribbon will last and how many impressions

it will satisfactorily record under normal working conditions.

Curved pressure fingers 6 conforming to an arc of the platen roll 1 and which hold the paper down smoothly against the same as it is being turned or fed are provided at each side of the type guide 3. They preferably and usually consist of flat metal strips. In the practice of my invention and to the ends above described, I provide two detachable clips which, on the occasion of a test, may be slipped into temporary engagement with these fingers and support a section of ribbon stretched in a fixed position across the printing point A. A preferred form of this clip is shown in position in Figures 1 and 2 and in detail in Figures 3, 4 and 5. It comprises a substantially flat plate having enlarged end portions 7 and 8 and a relatively narrow central waist portion 9 from which is struck up a tongue 10 projecting toward the enlarged end 5. Along the edge of this end portion 5 are arranged in a row a plurality of impaling pins 11 constituted in the present instance by striking up spurs from the metal sheet. At separated points along the length of the plate are two rounded bosses or protuberances 12 that may be made by bumping out the material as clearly shown in Figure 5.

In use, the plate is clipped over the pressure finger 6 with the waist portion 9 disposed beneath and the spring tongue 10 on top at a point just above the center of the platen roll 1. In some typewriter constructions the tongue thus lies between a roller 13 on the finger and a finger piece flange 14 struck up from the edge thereof. The ends of a section of ribbon indicated at B are impaled upon the respective sets of pins 11 so that the ribbon is drawn taut across the printing point A. The fingers 6 are usually slidably mounted toward and from each other along the length of the platen so that this operation is thereby additionally facilitated. The specimen ribbon is then immediately ready for the test in the manner first described.

While the platen and ribbon move together longitudinally they move relatively as the platen is turned and the paper is fed from line to line. The clip plate being held by the finger against the paper or platen is thus subjected to some frictional contact, but this is much reduced by the rounded bosses 12 against which the contact occurs and there is small likelihood of the clip being displaced. Additionally, the outer edge of the finger 6, because of its curvature, engages the shoulders formed at 15 by the enlarged end portion 8 which engagement is maintained to some extent by the ribbon itself and this also tends to prevent displacement of the clip plate. The bosses 12 being arranged, one on each side of the finger 6, equalizes the frictional pull upon the attachment due to the turning of the platen and feeding of the paper and act to further prevent the clip from being cocked or turned away. They also, in riding on the platen, space the clip away from the surface of the latter to make room for the paper when the paper strip is narrow and lies on the platen intermediate the clips.

In the preferred form of my invention as described, the attachment is symmetrical in form and no "rights" and "lefts" are required for the reason that either the upper two or the lower two of the impaling pins shown at 11 may be used according to whether the clip is applied to the finger 6 at the left or the one at the right, as will be understood from an inspection of Figure 1.

In the modified form of the invention shown in Figures 6 and 7 must be made in "rights" and "lefts", although it is a very simple construction. In that construction the body of the plate 9^a is provided with an extended serrated flange 11^a at one edge, the opposite edge being doubled back to form a spring tongue 10^a. This engages under the finger 6 as shown in Figure 7 and the body of the plate on the top of the finger. The ribbon is attached in the same manner.

I claim as my invention:

1. The combination with the platen of a typewriter having types cooperating therewith at a printing point and paper pressure fingers associated with the platen at each side of the printing point, of detachable sheet metal clips having spring tongues clipped over the fingers and provided with impaling points upon which an inking ribbon may be fixedly secured to stretch between the platen and the types across the printing point.

2. The combination with the platen of a typewriter having types cooperating therewith at a printing point and paper pressure fingers associated with the platen at each side of the printing point, of detachable sheet metal clips having spring tongues clipped over the fingers and provided with impaling points upon which an inking ribbon may be fixedly secured to stretch between the platen and the types across the printing point, said clips being further provided with rounded contact points projecting from their under sides to ride against the surface of the paper and platen when moved under it to reduce the frictional contact.

3. The combination with the cylindrical platen of a typewriter having types cooperating therewith at a printing point and curved paper pressure fingers associated with the platen at each side of the printing point, of detachable sheet metal clips having spring tongues clipped on the fingers and provided with impaling points upon which an inking ribbon may be fixedly secured to stretch between the platen and the types across the printing point, said clips being provided with

shoulders engaging the edges of the fingers to assist in maintaining their positions on the fingers.

4. As an article of manufacture, a clip for the purposes set forth comprising a metal plate having impaling points struck up therefrom, and a spring attaching tongue, the under side of the plate being provided with rounded frictionless bosses.
- 10 5. As an article of manufacture, a clip for the purposes set forth comprising a symmetrical metal plate having enlarged ends, one of which provides lateral inner shoulders, and a central waist portion having a spring 15 tongue struck up therefrom, the other enlarged end being provided with a plurality of impaling points for an inking ribbon, the end portions being embossed on their under sides to produce rounded anti-frictional projections.
